UNITED STATES PATENT OFFICE.

ABRAHAM LINCOLN TOWNSEND, OF IOLA, KANSAS.

OBSTETRICAL FORCEPS.

1,085,953.

Specification of Letters Patent.

Patented Feb. 3, 1914.

Application filed April 15, 1913. Serial No. 761,375.

To all whom it may concern:

Be it known that I, ABRAHAM L. TOWNSEND, a citizen of the United States, residing at Iola, in the county of Allen and State 5 of Kansas, have invented a new and useful Obstetrical Forceps, of which the following is a specification.

The invention relates to improvements in obstetrical forceps.

10 The object of the present invention is to improve the construction of obstetrical forceps, and to provide a simple, inexpensive and efficient instrument designed for facilitating the delivery of various animals, especially 15 pigs, and adapted to firmly grip a young pig or other animal around the neck, and capable of extracting such animal without liability of crushing its skull.

A further object of the invention is to 20 provide an instrument of this character having smooth gripping jaws to avoid injuring either a pig or a sow, and provided also with handles adapted to indicate the position of the jaws, so that after the same have 25 been introduced into an animal, they may be opened and closed with accuracy.

With these and other objects in view, the 30 invention consists in the construction and novel combination of parts hereinafter fully described, illustrated in the accompanying drawing, and pointed out in the claim here- 35 to appended; it being understood that various changes in the form, proportion, size and minor details of construction, within the scope of the claim, may be resorted to without departing from the spirit or sac- 40 rificing any of the advantages of the in- vention.

In the drawing:—Figure 1 is a perspective view of obstetrical forceps, constructed 45 according to this invention, and shown closed. Fig. 2 is a longitudinal sectional view of the same, the jaws of the forceps being open. Fig. 3 is a transverse sectional view, the jaws being shown closed in full lines and open in dotted lines. Fig. 4 is a detail perspective view of one of the bearing bushings.

Like numerals of reference designate cor- 50 responding parts in all the figures of the drawing.

In the accompanying drawing in which is 55 illustrated the preferred embodiment of the invention, the obstetrical forceps, which are designed to be constructed of steel or other

suitable material and finished in any desired manner to enable the instrument to be sterilized, comprise in their construction a tubular rod or stem 1 provided at its inner or rear end with a suitable handle 2, and equipped at its terminals with inner and outer bearing bushings 3, constructed of suitable metal and having parallel bores or openings 4, arranged in alinement and receiving a pair of parallel rock shafts 5. The bushings 3, which may be secured within the ends of the tubular stem in any suitable manner, form solid terminal bearings, and their openings are longitudinally alined and support the inner and outer portions of the shafts 5 and maintain the latter in spaced parallel relation, as clearly illustrated in Fig. 2 of the drawing. The handle 2, which may be secured to the rod or stem 1 in any desired manner, may be constructed of metal 75 or any other suitable material, and it may be of any preferred form and it enables the instrument to be firmly held while operating the same.

The shafts 5, which consist of rods, are 80 provided at their outer ends with approximately semicircular jaws 6, arranged to swing transversely of the instrument to open and close the forceps and having their terminal portions operating in contiguous 85 planes, so that the outer ends of the jaws will slide on each other in the closing movement of the instrument. The curved jaws, which swing transversely of the instrument, are adapted when closed to form a substan- 90 tially circular loop to encircle and fit the neck of an animal. The jaws, which present smooth inner and outer faces, are adapted to be introduced into an animal without injuring the same and after such 95 insertion, they may be opened and placed around the neck of the offspring. In order to afford greater protection to both the young and old animal, the jaws 6 are covered with yieldable material preferably 100 consisting of small rubber tubes 6^a, ar- ranged on the arms and adapted to be readily removed therefrom for sterilizing the instrument. To enable the position of the jaws under such conditions to be ascer- 105 tained with accuracy, the shafts are pro- vided at their inner or rear ends with ap- proximately straight operating arms 7 re- ceiving a loop or link 8 of substantially ob- long form having a longitudinal opening 110

9 through which the arms 7 pass. The operating arms are located beyond the end of the handle, and the operator is adapted to grasp the handle with one hand and the 5 operating arms with the other hand and manipulate the same without interfering with his grip on the handle of the instrument. The arms, which extend in the same general direction as the jaws, are provided 10 at their outer sides with notches 10, adapted to be engaged by the link or loop 8, which retains the jaws in engagement with a pig or other animal. The arms 10 are adapted to swing transversely of the instrument to open and close the jaws, and their 15 outer terminals 11 are bent in opposite directions to form stops for retaining the loop or link on the arms. The jaws, which positively embrace and firmly grip an animal around the neck, are arranged substantially out of the way when in their engaging position, so that they will not lacerate or 20 otherwise injure a sow or other animal, and

the instrument enables a pig or other animal to be easily extracted. 25

What is claimed is:—

An instrument of the class described including a stem consisting of a tube, inner and outer bushings mounted within the stem and having parallel bearing openings, 30 shafts extending through the stem and journaled in the said bearing openings and provided at their outer ends with jaws arranged to swing transversely of the instrument to open and close the same, said shafts 35 being provided at their inner ends with operating arms for opening and closing the jaws.

In testimony, that I claim the foregoing as my own, I have hereto affixed my signature in the presence of two witnesses.

ABRAHAM LINCOLN TOWNSEND.
